CLAIM

The ornamental design for a wall sconce, as shown and described.

DESCRIPTION

FIG. 1 is a top perspective view of a wall sconce, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view showing the wall sconce in an alternate state; and,

FIG. 10 is a top perspective view showing the wall sconce in another alternate state.

The broken lines in the drawings illustrate the portions of the wall sconce, which form no part of the claimed design.

1 Claim, 10 Drawing Sheets
